The diagram illustrates a mechanical system. It features a vertical column with a base labeled d . A horizontal beam, labeled h , is attached to the right side of the column. A spring, labeled k , connects the base d to the beam h . A vertical line, labeled σ , extends from the base d upwards through the column. A horizontal line, labeled τ , extends from the beam h to the right. A vertical dashed line, labeled σ , is positioned to the right of the column. A horizontal dashed line, labeled τ , is positioned below the beam h .

UNITED STATES PATENT OFFICE.

HENRY J. JACOBS, OF BUFFALO, NEW YORK, ASSIGNOR TO BUFFALO LOUNGE COMPANY,
OF BUFFALO, NEW YORK.

SOFA-BED.

1,148,019.

Specification of Letters Patent. Patented July 27, 1915.

Application filed November 18, 1912. Serial No. 732,033.

To all whom it may concern:

Be it known that I, HENRY J. JACOBS, a citizen of the United States, residing at Buffalo, in the county of Erie and State of New York, have invented a new and useful Improvement in Sofa-Beds, of which the following is a specification.

This invention relates to sofa beds or convertible couches especially of the davenport type which have a hinged seat adapted to be swung to an inverted position in front of the couch and a folding spring bed bottom which, with the mattress carried thereby, is adapted to be unfolded or extended to form a bed above the couch seat when the latter is inverted, and to be folded beneath the couch seat when the seat is returned to its normal position.

The object of the invention is to produce a practical, desirable and comfortable sofa bed of this type, which is of a novel construction enabling the same to be produced at a moderate cost, which insures ease of operation, and in which the length or greater dimension of the bed bottom when extended or unfolded extends crosswise with reference to the couch instead of lengthwise thereof, so as to enable the provision of a full size bed in a couch which is but slightly longer than the width of the bed.

In the accompanying drawings, consisting of three sheets: Figure 1 is an elevation, partly in section, of a sofa bed embodying the invention, showing the bed bottom extended to form the bed. Fig. 2 is a fragmentary plan view, on an enlarged scale, of one end of the folding spring bottom frame. Fig. 3 is a section thereof, partly in plan, on line 3—3, Fig. 1. Fig. 4 is an inside elevation of the joint between the outer and intermediate bed bottom sections. Fig. 5 is an elevation, partly in section, of the couch showing the outer bed bottom section about to be folded. Fig. 6 is a fragmentary similar sectional elevation thereof showing the outer bed bottom section folded over on the intermediate section. Fig. 7 is a fragmentary sectional elevation thereof showing the same closed for use as a couch. Fig. 8 is a front elevation partly in longitudinal section, in line 8—8, Fig. 7. Fig. 9 is a section of the bed bottom on line 9—9, Fig. 1.

Like reference characters refer to like parts in the several figures.

A represents the stationary frame of the couch which may be of any suitable construction. The couch illustrated is of the davenport type and this frame consists of a rigid rectangular base portion, high ornamental end pieces or arms *a*, and a stationary upholstered back *a'*.

B represents the couch seat, which, as usual, consists of a rectangular box-like frame *b* and an upholstered seat pad *b'* which is yieldingly supported by a suitable spring bottom contained in the frame *b*. The front board of the seat frame is hinged at its lower portion or edge to the upper edge or portion of the front rail of the stationary couch frame by suitable hinges *C* which permit the seat to be swung forwardly and downwardly from the normal seat forming position, shown in Fig. 7, to the inverted position in front of the stationary frame, shown in Figs. 1, 5 and 6.

The folding spring bed bottom or mattress support consists of the usual resilient fabric *D*, composed of flexibly connected links or of other formation, which is attached at its sides and ends to a folding rectangular frame. This frame is preferably made of metal angle bars and consists of inner and outer end bars *d* and *d'* connected by folding sectional side bars, each composed of three main or principal sections *d'*, *d* and *d* of approximately equal length, and a short spacing section *d* which connects the outer and intermediate sections *d'* and *d*.

The intermediate and inner sections *d*, *d* are connected at their adjacent ends by suitable hinges *d* which project upwardly from the frame when the bed bottom is extended as shown in Fig. 1, so that when the frame is folded these hinges hold apart or space the ends of the sections to which they are attached, to provide room between the sections for the folded mattress, which is indicated at *D'*.

The inner bottom frame section *d* is movably supported in the stationary couch frame by suitable means so as to rise and fall, and the other sections of the bed bottom frame are mounted on the hinged seat so as to turn with the seat when it is swung to and from its inverted position. In the construction shown, the inner section is connected at its inner or rear edge to links *e* which are suitably pivoted to the ends of

the stationary couch frame. These links have a pin and slot or other suitable sliding connection with the bars d^3 of the inner bed bottom section, and braces or links e' pivoted to the side bars d^3 have pin and slot or other suitable sliding connections with the links e . The bars d^2 forming the intermediate section of the bed bottom frame are pivoted or hinged at f in any suitable way 10 to rigid posts f' at the ends of the couch seat near the hinged side thereof, which posts project upwardly from the seat when it is inverted, and downwardly from the seat when it is in its normal position. The seat 15 is provided adjacent to its rear or free edge with rigid end posts f^2 which also project upwardly from the seat when it is inverted.

Links G pivoted at one end to the bars d^4 of the spacing section of the bed bottom, 20 have pin and slot or other suitable sliding connections at g with the posts f^2 , and the opposite ends of these links G have pin and slot or other suitable sliding and pivotal connections at g' with the bars d^2 of the intermediate frame section. When folding the bed bottom from its extended or bed-forming position, shown in Fig. 1, the outer section is raised and the links G are adapted 25 to slide and swing on the posts f^2 and also at their connections with the intermediate section, thus permitting the adjacent end of the intermediate section to fall into the seat frame as shown in Fig. 5, the intermediate section swinging on its hinged connections 30 f with the seat posts f' . These connections permit the short or spacing section d^4 to swing with the outer section d' to the substantially upright position shown in Fig. 5. The links G prevent the spacing section d^4 35 from swinging inwardly beyond the upright position, but the outer section d' is adapted to fold at its pivotal connections with the spacing section d^4 over on the intermediate section d^2 . The spacing section d^4 thus holds 40 the adjacent edges of the intermediate and outer sections apart and provides ample room between them for the folded mattress D' . After the outer section has been folded over on the intermediate section as explained and as shown in Fig. 6, the seat B 45 can be swung upwardly and rearwardly to its normal or seat forming position, and when the seat is thus returned to its normal position the supporting links for the inner bed bottom section and the hinges between the latter and the intermediate section permit the inner section to fall into the stationary frame and the folded intermediate and outer bed bottom sections to fold over above 50 the inner section, as shown in Fig. 7. When thus folded, the hinges d^5 between the inner and intermediate sections provide sufficient room between the hinged edges of these sections to accommodate the folded mattress 55 and the outer end of the mattress and the

outer bed bottom section which is located between the inner and intermediate sections.

The horizontal flanges of the bars d^4 of the short or spacing section of the bed bottom frame overlap the horizontal flanges of 70 the intermediate and outer sections when the bed bottom is extended as shown in Figs. 2 and 4, and thus coöperate with the links G in holding the frame rigid and preventing it from sagging or bending downwardly at 75 the connections of the outer section to the intermediate section. The ends of the horizontal flanges of the bars d^4 also act as stops to prevent the spacing section from swinging beyond a substantially upright position 80 when folding the bed bottom.

The bed bottom fabric is preferably connected to the folding sides of the bed bottom frame by the usual springs which afford the necessary resilience for the bed 85 bottom, and in order to prevent the strain, due to the pull of these springs and the weight of the occupant of the bed, from springing the folding sides of the frame inwardly, the bars d^4 of the spacing section 90 are connected by a rigid brace or bar H , which extends from side to side of the folding bed bottom frame beneath the flexible fabric.

Legs I of any suitable sort may be employed for supporting the couch seat in its inverted position. The legs shown are pivoted in sockets on the ends of the seat adjacent to its free or rear edge and are adapted, when the seat is returned to its 100 normal position, to swing down between the ends of the seat and the ends of the couch to the position indicated in Fig. 7, so as to be hidden from view.

K represents folding legs for supporting 105 the outer end of the outer bed bottom section. These legs are preferably rigidly connected by a cross bar k and are hinged or pivoted in any suitable manner at k' to the end of the outer bed bottom section so as to 110 swing down against said section when the section is swung upwardly in folding the bed bottom. The legs K are provided with projecting latch bars L which, when the outer bed bottom section is folded over the intermediate section, are adapted to engage with studs l projecting from the ends of the intermediate section, to hold the outer and intermediate sections from relative movement 115 when the couch seat is turned upwardly to its normal position. As shown, the latch bars are provided with notches which the studs l are adapted to enter, and the weight of the legs K tends to hold the latch bars in 120 connection with the studs. In opening the bed after the couch seat has been inverted, thus partially unfolding the bed, the cross bar k connecting the legs K is grasped to turn the outer bed bottom section over to its horizontal position, and the pull on the legs 125 130

K, disengages the latch bars L from the studs l so as to release the outer section.

l' represents braces connecting the latch bars L to the legs for holding the latch bars 5 rigid.

M represents springs attached to the posts f' on the couch seat and the ends of the stationary couch frame for counterbalancing the weight of the seat and the bed bottom, 10 and assisting in the movement of the parts when opening and closing the bed. These springs or other suitable means for the purpose may be employed or not, as desired.

By constructing and mounting the bed bottom as described, with the inner section movably supported by the stationary frame A and the other sections carried by the couch seat, the seat can be hinged to the front of the couch by ordinary hinges of an 20 inexpensive kind, and hinges and fittings of special design and more expensive construction are avoided. Simple pivotal connections are also used for connecting the sections of the bed bottom frame to each other and 25 to the couch seat, and the parts are few in number and of inexpensive construction. For instance, but one pair of plain bar links is used in addition to the bar sections of the bed bottom, for permitting the described 30 folding of the outer and intermediate sections and for rigidly supporting them when the bed is extended. Nevertheless, the couch can be operated readily and with but little exertion in converting it from sofa to 35 bed and vice versa, and when the bed bottom is extended, the flexible spring bottom fabric is supported by its frame from end to end and side-to-side, above and clear of the couch seat or other underlying parts of the couch, 40 so that it will afford the same comfort as the ordinary bed with a non-folding spring bottom or bed spring. The bed thus formed is essentially more comfortable and desirable than one which is formed in part by an 45 upholstered part of the couch seat or back.

I claim as my invention:

1. In a sofa bed, the combination of a stationary frame, a couch seat which is hinged to said frame and is adapted to be 50 inverted in front thereof, and a folding bed bottom having a frame comprising connected inner, outer and intermediate sections, said intermediate section being mounted on the underside of said couch seat and 55 supported above the same when the seat is inverted, said inner section being movably

mounted on said stationary frame and connected to said intermediate section by means which space said sections apart when the bed bottom is folded, and said outer section 60 being supported at its inner edge by said couch seat, and supporting means for the outer edge of said outer section, substantially as set forth.

2. In a sofa bed, the combination of a 65 stationary frame, a couch seat which is hinged to said frame and is adapted to be inverted in front thereof, and a folding bed bottom having a frame comprising connected inner, outer and intermediate sec- 70 tions arranged to fold with said outer section between said intermediate and inner sections, said intermediate section being hinged to said inner section and hinged to supports which rise from the hinged side 75 of said couch seat when the seat is inverted, a spacing section connecting said outer and intermediate sections, links connected to said spacing section and having sliding and swinging connections with said intermediate 80 section and with supports on said couch seat, movable supporting means connecting said inner section with the stationary frame, and supporting means for said outer section, substantially as set forth. 85

3. In a sofa bed, the combination of a supporting member, a bed bottom frame including two sections pivoted together, and a link pivoted to one of said sections and pivotally and slidably connected to the other of 90 said sections, said link being pivotally connected between its ends to said support, substantially as set forth.

4. In a sofa bed, the combination of a 95 stationary frame, a couch seat adapted to be inverted in front of said frame, and a folding bed bottom frame including sections pivoted together, one of said sections being pivoted at one end to said seat, and a link pivoted at one end to one of said sections 100 between the ends of said section and pivotally and slidably connected at the other end to the other of said sections between the ends of said section, said link being pivotally and slidably connected between its ends to 105 said seat, substantially as set forth.

Witness my hand, this 14th day of November, 1912.

HENRY J. JACOBS.
